ABSTRACT OF THE DISCLOSURE

Means for converting liquid fuel to a vapor to be used in a burner, which means comprises a vaporization chamber disposed to receive heat from the burner, means for selectively and adjustably positioning the chamber relative to the burner thereby to control the vaporization of fuel in the chamber, first conduit means for connecting the chamber to a pressurized fuel source and second conduit means for connecting the chamber to a burner control means and through the control means to the burner. Preferably, a thermostat is arranged to sense the temperature of the vapor in the second conduit means and to deenergize the burner when such temperature reaches a predetermined level. Further, pressure regulating means is disposed in the second conduit means selectively and adjustably to establish the pressure of the fuel supplied to the burner.

BACKGROUND OF THE INVENTION

Field of the invention.—The present invention relates to gas-fired heaters, and more particularly to the provision of means for converting liquid fuel to a vapor to be used in the burner of such a heater.

Description of the prior art.—Conventionally, heaters arranged to burn fuels such as propane gas are connected to the top of a tank which contains the gas under pressure. Thus, the vapor at the top of the tank is fed to the burner. As the vapor is drawn from the tank, the liquid in the tank absorbs heat to produce more vapor. If the ambient temperature is lower than, say 40° F., and if the rate of usage of vapor is sufficiently great, the tank will "freeze" and the conversion from liquid to vapor will be halted. Generally, when a tank "freezes," a coating of ice will develop on the tank. When such an icing condition exists, there simply is not enough heat, commonly called the heat of vaporization, to vaporize the liquid propane.

This problem is particularly acute when propane burners are utilized in grain-drying equipment. Generally, farmers must dry their grain using such equipment during the fall and early winter.

SUMMARY OF THE INVENTION

It is a primary object of the present invention to provide an improved heater of the type comprising a vapor burner and means for controlling the flow of fuel to the burner, wherein the improvement comprises means for connecting the burner to a pressurized liquid fuel source. The improved heater of the present invention can be connected to the lower end of a pressurized propane tank to draw liquid propane from the tank.

Specifically, the means for connecting the burner to the fuel source comprises a vaporization chamber disposed to receive heat from the burner and means for selectively and adjustably positioning the chamber relative to the burner. First conduit means are provided for connecting the chamber to the fuel source and second conduit means are provided for connecting the chamber to the control means for the burner and through the control means to the burner. In the heater of the present invention, the liquid fuel is converted to a vapor in the chamber and the required heat of vaporization is provided by the

2

burner. The vapor leaves the chamber and flows to the burner.

An appropriate pressure regulating valve is disposed between the chamber and the burner to regulate the pressure of the vapor supplied to the burner, the vapor pressure at the input side of such regulating valve being substantially equal to the pressure of the fuel in the fuel tank.

Preferably, a thermostat is arranged to sense the temperature of the vapor in the second conduit means, i.e., the temperature of the vapor leaving the chamber and flowing toward the burner, and to operate the control means to deenergize the burner when the temperature of the vapor in the second conduit means reaches a predetermined level.

The improvement of the present invention can be provided as a conversion kit for converting burners presently arranged to accept only vapor, such as that provided at the top of a pressurized propane tank, so that the burners can utilize liquid fuels, such as liquid propane.

Another object of the present invention is to provide such an improved heater comprising means for selectively and adjustably positioning the vaporization chamber relative to the burner, thereby to control the vaporization of the fuel in the chamber.

The above-mentioned and other features and objects of this invention and the manner of attaining them will become more apparent and the invention itself will be best understood by reference to the following description of an embodiment of the invention taken in conjunction with the accompanying drawings wherein:

BRIEF DESCRIPTION OF THE DRAWINGS

FIG. 1 is a perspective view, partially cut away, showing the improvement of the present invention embodied in a conventional grain-drying heater;

FIG. 2 is an elevation view showing means for supporting the vaporization chamber in the heater; and

FIG. 3 is an exploded perspective view of the preferred vaporization chamber and its mounting means.

DESCRIPTION OF THE PREFERRED EMBODIMENT

Referring now to the drawings, and particularly to FIG. 1, it will be seen that there is illustrated a heater, indicated generally by the reference numeral 10, the heater comprising a gas burner 12 arranged to direct a flame generally in the direction of the arrow 14 and a burner control means, indicated generally by the reference numeral 16. A blower, not shown, is mounted in the end 18 of the heater 10 and arranged to direct air in the direction of the arrow 14.

Conventional spreader vanes 20 are conically arranged about the burner 12 as clearly shown in FIG. 1.

The burner 12 is arranged to receive fuel in vapor form. The control means 16 includes conventional electrically-operated valves for controlling the flow of vapor to the burner 12, one such valve being indicated by the reference numeral 22.

The improvement of the present invention comprises a toroidally-shaped chamber 24 which serves as a vaporization chamber, i.e., a chamber in which liquid fuel is converted to vapor. The chamber 24 is positioned forwardly of the burner 12 to receive heat therefrom.

As clearly seen in FIGS. 1 and 3, a transverse, fluid-tight partition 26 is provided in the chamber 24. Connected to the chamber 24 on one side of the partition 26 is a rigid pipe 28 and connected to the chamber 24 on the other side of the partition 26 is another rigid pipe 30. A shut-off valve 32 and a pressure-relief valve 34 are connected to the free end of the pipe 30 as shown in FIG. 1, the pressure-relief valve 34 being disposed between the shut-off valve 32 and the chamber 24. The pipe

30 and the passages through the shut-off valve 32 and pressure-relief valve 34 comprise conduit means for connecting the chamber 24 to a pressurized fuel source, such as a propane tank. It will be understood that the chamber 24 is to be connected to the fuel source to receive liquid fuel.

The free end of the pipe 28 is connected through an elbow fitting 36 to a pressure-regulating valve 40, the output side of the valve 40 being connected through a relatively long tube 42 and fittings, indicated generally by the reference numeral 44, to the electrically-operated valve 22 and through that valve 22 to the burner 12. Thus, the pipe 28, elbow fitting 36, the passage through the regulating valve 40, tube 42 and fittings 44 all comprise second conduit means for connecting the chamber 24 to the control means 16 and through the control means 16 to the burner 12.

The liquid fuel entering the chamber 24 through the pipe 30 is heated and converted into a vapor usable in the burner 12. The necessary heat for converting the liquid to a vapor is provided by the burner 12. The vapor leaving the chamber 24 flows through the pipe 28 and the elbow fitting 36 to the pressure-regulating valve 40. The pressure of the vapor at the input side of the regulating valve 40 is substantially equal to the pressure of the fuel in the fuel source connected to the chamber 24. Generally, the pressure-relief valve should prevent gas pressures from exceeding 300 p.s.i. Also, generally, the regulating valve 40 is set to provide vapor to the burner 12 at pressures from 5 to 30 p.s.i.

A thermostat 46 is mounted on the tube 42 adjacent to fittings 44 and is connecting to a high limit thermostat 48 comprising a portion of the control means 16, the thermostat 46 being arranged to sense the temperature of the vapor in the tube 42 and to operate the control means 16 to deenergize the burner 12 when the temperature of the vapor in the tube 42 reaches a predetermined level, of, for example, 225° F. That is, if the temperature of the vapor leaving the chamber 24 reaches a level which could cause damage to the components comprising the control means 16, the burner 12 will be deenergized.

It is desirable to heat the chamber 24 to a point sufficient to vaporize completely the liquid fuel contained therein. If the fuel is not being sufficiently heated, the pipe 28 and tube 42 will tend to accumulate a coating of ice or frost, thereby indicating that further vaporization is taking place therein. If the pipe 28 and the tube 42 tend to accumulate a coating of ice or frost, the chamber 24 should be moved closer to the burner 12. On the other hand, if the thermostat 46 operates the control means 16 to deenergize the burner 12, the chamber 24 should be moved slightly away from the burner 12.

The two pipes 28 and 30 extend through and are supported by a mounting plate 50 as shown in FIGS. 1 and 3. Specifically, a pair of mounting collars 52 and 53 is rigidly mounted on the plate 50 to extend generally perpendicularly therefrom, each collar 52, 53 being aligned with an aperture 54, 55 in the mounting plate 50. The pipe 28 is slidably received in the collar 52 and the pipe 30 is slidably received in the collar 53. A screw 56 is threaded into each collar 52, 53 (FIG. 3) to engage the pipe 28, 30 extending therethrough. Thus, when the screws 56 are loosened, the chamber 24 can be moved in the direction of the pipes 28 and 30 to position the chamber 24 transaxially relative to the burner 12.

The mounting plate 50 is provided to cover an opening, not shown, in the outer, cylindrical wall 67 of the heater 10, the mounting plate 50 being fastened to the heater 10 by means of the four screws 58, each of which extends through an opening 60 in the mounting plate, each opening 60 being elongated in a direction generally parallel to the arrow 14. Thus, the mounting plate 50 is adjustably movable in a direction generally parallel to the arrow 14 which is parallel to the axis of the toroidally-shaped chamber 24.

In the preferred embodiments of the present invention, a brace rod 62 is arranged to provide additional support for the chamber 24, one end of the brace rod 62 being connected to the chamber 24 as indicated at 64 and the other end of the brace rod 62 being connected to the wall of the heater 10 as indicated at 66.

The connection 66 is shown clearly in FIG. 2. Referring to FIG. 2, it will be seen that the brace rod 62, which is threaded as illustrated, is secured to the wall 67 of the heater 10 by means of the illustrated nuts 70 and 71, a washer 72 and another mounting plate 73. Specifically, the rod 62 extends through an opening 68 in the wall 67 and the nut 70 holds the washer 72 against the inside surface of the wall 67 while the nut 71 holds the mounting plate 73 against the outside surface of the wall 67.

It can be seen that, by loosening the nuts 70 and 71 and the screws 56 securing the pipes 28 and 30 relative to the mounting plate 50, the chamber 24 can be adjustably moved in the direction of the pipes 28 and 30. Likewise, by loosening the nuts 70 and 71 and the screws 58, the mounting plate 50 can be adjustably moved in the direction of the elongated slots 60. Usually, the axis of the chamber 24 will be generally coincident with the axis of the heater 12.

The vaporizer of the present invention eliminates the need for extra large or additional propane gas tanks and eliminates the problem of tank "freeze-up." The vaporizer will permit the use of liquid propane as a fuel supply for a vapor gas burner.

The chamber 24 is preferably constructed from heavy steel piping designed safely to withstand high operating temperatures and gas pressures. In the illustrative embodiment, the chamber 24 is provided by welding together a pair of 180° elbows with the partition 26 inserted as shown clearly in FIG. 3, the welds being indicated at 75 and 76. The pipes 28 and 30 are preferably steel pipes welded to the chamber 24 as indicated at 77 and 78, respectively, in FIG. 3.

While there have been discussed above the principles of this invention in conjunction with specific apparatus, it is to be clearly understood that this description is made by way of example and not as a limitation to the scope of the invention.

What is claimed is:

1. An improved heater of the type comprising a burner arranged to be connected to a pressurized fuel source and means for controlling the flow of fuel to said burner; wherein the improvement comprises means for connecting the burner to such fuel source, said connecting means comprising means defining a vaporization chamber for such fuel spaced from said burner and disposed to receive heat therefrom, first conduit means for connecting said chamber to such fuel source, second conduit means connecting said chamber to said control means and through said control means to said burner, means for selectively varying the spacing of said chamber from said burner thereby to control the vaporization of such fuel in said chamber when said burner is energized, and a thermostat dominating said control means, said thermostat being arranged to sense the temperature of the vapor in said second conduit means and to operate said control means to deenergize the burner when the temperature of said vapor reaches a predetermined high value, said varying means being adjusted so that the spacing of said chamber from said burner is such that the temperature of the vapor in said second conduit means is normally less than said high value.

2. An improved heater as in claim 1 wherein said chamber is toroidally shaped, said chamber being generally axially aligned with said burner and spaced forwardly thereof, said chamber having a transverse, fluid-tight partition therein, said first conduit means being connected to said chamber on one side of said partition and said second conduit means being connected to said cham-

ber on the opposite side of said partition; said varying means comprising a mounting plate through which portions of said first and second conduit means extend, said chamber being supported on such portions, first means for mounting said mounting plate on said heater for selectively adjustable movement in a direction generally parallel with the axis of said chamber, a brace rod for additionally supporting said chamber in said heater, means rigidly connecting one end of said brace rod to said chamber, and second means for mounting the other end of said brace rod on said heater for selectively adjustable axial movement of said chamber; and further comprising pressure regulating means disposed in said second conduit means and arranged selectively and adjustably to establish the pressure of the fuel supplied to the burner, the pressure at the input side of said regulating means being generally equal to pressure of such fuel source, a pressure relief valve disposed in said first conduit means, and a selectively actuatable valve disposed in said first conduit

means between such fuel source and said pressure relief valve.
